PRINTING DEVICE

James P. Jackson, Chicago, Ill., assignor to
Addressograph Company, Wilmington, Del., a
corporation of Delaware

Application October 17, 1930, Serial No. 489,278

14 Claims. (Cl. 129—16.8)

This invention relates to printing devices of the kind adapted to be stored in cabinets according to a predetermined classification and to be sequentially passed through addressing or printing machines after which the devices are collected and returned to storage in the cabinet drawers without disturbing the classified arrangement thereof. It has been the custom to provide the printing devices with a plurality of keepers to receive detachable tabs in selected positions, but there is liability that the detachable tabs may be separated from the devices while the devices are being handled or passed through the machine, which would result in confusion of the classification. Furthermore, it has been customary to provide the printing devices with spacing flanges so that the bodies of the devices will be spaced one from the other when stored in the drawers in order that the faces of the type characters embossed on the bodies will not be damaged. Moreover, it has been found desirable, in the use of printing devices of this character, to provide an arrangement whereby the tabs may be secured to the devices with either of the faces thereof disposed toward the printing faces of the devices.

One of the objects of the present invention, therefore, is to provide a novel printing device to which a detachable tab may be firmly secured, with either face of the tab disposed toward the printing face of the plate.

Another object of the invention is to provide a printing device having spacing flanges so formed that the likelihood of the edges of other printing devices engaging the free edges of the flanges, in the handling and arranging of the printing devices, is obviated.

A still further object of the invention is to provide a printing device wherein the body on which the printing characters are embossed is depressed below the plane of the face of the printing device, opposite the face provided with the spacing flanges, in order that the thickness of the device through the printing characters may be kept at a minimum.

In the selected embodiment of the invention illustrated in the accompanying drawing

Fig. 1 is an elevational view of the printing face of a printing device made in accordance with my invention;

Fig. 2 is a longitudinal sectional view taken substantially on the line 2—2 on Fig. 1;

Fig. 3 is a transverse sectional view taken substantially on the line 3—3 on Fig. 1;

Fig. 4 is a fragmentary elevational view of

the face of the printing device opposite that depicted in Fig. 1;

Fig. 5 is a fragmentary longitudinal sectional view taken substantially on the line 5—5 on Fig. 1;

Fig. 6 is a fragmentary transverse sectional view, showing the tab and the keeper arrangement therefor, taken substantially on the line 6—6 on Fig. 1; and

Fig. 7 is a perspective view of a tab of the character used in connection with my improved printing device.

The printing device shown in the accompanying drawing comprises a body, generally indicated by 8, formed from sheet metal and of substantially rectangular formation. Along the opposite longer edges of the body 8 the margins are folded upon the body to provide flanges 9, 9, these flanges terminating inwardly of the shorter edges of the body. Along the shorter edges of the body the margins are bent to provide substantially triangularly shaped spacing flanges 10, 10 which have the apices thereof disposed outwardly of the face of the body 8 opposite the face on which the flanges 9, 9 are disposed, and the marginal portions 11, 11 outwardly of the spacing flanges are then folded inwardly across the open bases of the triangularly shaped spacing flanges, and the edges of these marginal portions abut the ends of the flanges 9, 9. In this manner, the adjacent face of the body 8 is disposed below the plane of the outwardly disposed faces of the flanges 9, 9 and the marginal portions 11, 11 and in effect, this face is depressed. The printing characters 12 are so embossed on the body that the relief faces thereof are disposed on this depressed face and the printing characters extend but slightly beyond the plane of the outwardly disposed faces of the flanges 9, 9 and the marginal portions 11, 11.

When the printing devices are properly arranged in storage drawers or the like the spacing flanges 10, 10 of one printing device will rest on the marginal portions 11, 11 of the adjacent printing device, which portions provide abutment or seating surfaces. The spacing flanges are of a size sufficient to space the printing devices apart in such an amount that the relief faces of the printing characters 12 on one printing device will be prevented from contacting with the face of an adjacent printing device. By forming the spacing flanges 10, 10 in

the manner above described no free edge portions are formed on the intaglio face of the printing device. Thus when the printing devices are being handled the edges thereof will freely move over the spacing flanges, thus facilitating alignment there-

of. This facile alignment is also aided by the smooth edges of the printing devices which are produced by the folding of the marginal portions in the above described manner, and these smooth edges, together with the smooth edges of the spacing flanges, greatly facilitate the accomplishment of the desired object.

It is customary to provide printing devices with detachable tabs to facilitate classification thereof. In the present instance means are provided whereby such detachable tabs may be easily secured in the frame, and these means are so arranged that the tab will be firmly held therein to prevent displacement therefrom. Below the flange 9, along what may be termed the upper edge of the printing device, the body 8 has slits 13 and 14 provided therein which are arranged in pairs, the number of these pairs of slits provided in each plate being determined by the length thereof. These slits are formed by striking up portions of the body 8, and these struck-up portions of the body 8 provide keepers 15 and 16, the keepers 15 and 16 being joined to the body along the opposite edges thereof, and the keepers include portions which extend parallel to, but in spaced relation with, the body and by reason of the joining of the keepers to the body along opposite edges of the keepers it is manifest that the keepers open toward each other. Therefore, the stem of a tab is adapted to be inserted between the keepers and to prevent displacement of the stem from the keepers suitable locking means are provided. One of the keepers, which in the present instance is the keeper 16, is embossed substantially medially between the ends thereof and thereby a projection 17 is provided which extends toward the printing face of the printing device. A tab of the character used in connection with the disclosed printing device is illustrated in Fig. 7 and includes a stem 18 that is narrower than the main body of the tab and which therefore defines shoulders 19, 19 on the tab 20. The stem 18 is embossed substantially medially in the extent thereof. Two transversely aligned embossages 21 and 22 are provided in the stem on opposite sides of the center line thereof and these embossages project in opposite directions from the face of the tab. The intaglio faces of the embossages provide pockets and the relief faces provide projections. When the tab is to be connected to the printing device the stem is passed between a pair of the keepers 15 and 16 and passed thereby until the pocket of one of the embossages 21 or 22 moves into alignment with the projection 17 which will snugly seat in this pocket, and at this time the shoulders 19, 19 engage the upper ends of the keepers 15 and 16. When the face of the tab opposite the face shown in Fig. 7 is disposed toward the printing face of the printing device, the projection 17 will fit in the pocket defined by the embossage 21. When the opposite face of the tab is to be disposed toward the printing face of the printing device, the projection 17 will fit in the pocket of the embossage 22. It is therefore manifest that either face of the tab may be disposed toward the printing face of the printing device. The tab is secured to the printing device in a manner which will obviate undesired displacement of the tab, for the side edges of the stem 18 neatly fit between the side edges of the keepers and the tab is locked in position by the seating of the projection 17 in one of the pockets. Moreover, the relief part of the embossage not engaged by the projection 17 will engage the inner face of the

unembossed keeper which, in the present instance, is the keeper 15.

From the foregoing description it is manifest that I have provided a printing device which may be readily stored in a drawer with other printing devices of a similar nature, for the spacing flanges are so arranged that they are free of exposed edges and therefore the printing devices will freely slide over one another. Furthermore, I have provided a printing device to which a detachable classification tab may be firmly connected, and I have so arranged the tab and the retention therefor that the tab may be positioned with either face thereof disposed toward the printing face of the printing device and therefore, if desired, different classification indicia may be provided on opposite faces of the tab, which is manifestly advantageous as it increases the number of possible classifications without increasing the number of tabs.

In the foregoing description I have set forth a selected embodiment of my invention, but it is to be understood that this is capable of variation and modification and I therefore do not wish to be limited to the precise details set forth but desire to avail myself of such changes and alterations as fall within the purview of the following claims.

I claim:

1. A printing device having a pair of keepers on one face and adjacent one edge thereof, said keepers extending side by side parallel with an edge of the printing device joining said one edge, each of said keepers being engageable with but one of the side edges of a tab inserted therebetween, said keepers including tab locking means positioned substantially midway between the ends of the keepers.

2. A printing device having keepers on one face and adjacent one side edge thereof, said keepers being parallel with the end edges of the printing device and being arranged in cooperating pairs, each keeper of a pair being engageable with but one of the side edges of a tab inserted therebetween, one of the keepers of each pair including tab locking means positioned thereon substantially midway between the ends thereof.

3. A substantially rectangular printing device having a pair of keepers on one face and adjacent one side edge thereof, said keepers being parallel with the end edges of the printing device, each of said keepers being engageable with but one of the side edges of a tab inserted therebetween, one of said keepers having a tab locking embossage thereon positioned substantially midway between the ends thereof.

4. A substantially rectangular printing device having a pair of keepers on one face and adjacent one side edge thereof, said keepers being parallel with the end edges of the printing device, each keeper being engageable with but one of the side edges of a tab inserted therebetween, one of said keepers having an embossage therein with the relief face of the embossage projected toward the face of the printing device, said embossage being positioned substantially midway between the ends of said keeper and being adapted to lock the tab inserted between said keepers against displacement.

5. A substantially rectangular printing device including a body having slits therein adjacent one side edge thereof provided by portions struck up from the body to provide keepers, said keepers being parallel with the end edges of the printing device and being arranged in cooperating

paifs, each of said keepers being engageable with but one of the side edges of a tab inserted therebetween, one keeper of each pair having a tab locking embossage thereon positioned substantially midway between the ends thereof.

6. The combination of a printing device having a pair of keepers thereon, one of said keepers having an embossage therein providing a projection positioned substantially midway between the ends of the keeper, and a tab including a stem portion having an embossage therein providing a pocket positioned substantially midway between the ends of said stem portion whereby when said stem portion is passed between the ends of the keeper, the projection on said keeper will seat in the pocket on said stem to lock said tab to said printing device.

7. The combination of a printing device having a pair of keepers thereon, one of said keepers having an embossage therein providing a projection positioned substantially midway between the ends of the keeper, a tab including a stem portion having shoulders thereon whereby when said stem is neatly fitted between said keepers said shoulders engage the adjacent end of said keepers, said tab having an embossage in the stem portion thereof providing a pocket positioned substantially midway between the ends of said stem portion to cooperate with the projection on said keeper to lock said tab against displacement from said printing device when said stem portion is disposed between said keepers with said shoulders in abutment with the adjacent ends of said keepers.

8. The combination of a printing device having cooperating pairs of keepers thereon, one keeper of each pair having an embossage therein providing a projection, a tab including a stem portion having shoulders thereon whereby when said stem portion is neatly fitted between a pair of said keepers said shoulders will engage the adjacent ends of said keepers, said tab having oppositely extending embossages therein providing pockets whereby when said tab is disposed with the stem thereof between said keepers and said shoulders engaging the ends of said keepers one of the dents in said stem will cooperate with the projection on said keeper to secure said tab to said printing device.

9. The combination of a printing device having a cooperating pair of keepers thereon, one of said keepers having an embossage therein providing a projection, a tab including a stem portion adapted to be neatly fitted between said keepers, said tab having an embossage therein providing a pocket adapted to cooperate with the projection on said keeper when said stem is disposed between said keepers, and said tab having another embossage therein providing a projection adapted to cooperate with the adjacent part of the printing device to position said tab in said keepers with the pocket on the tab in engagement with the projection on the keeper.

10. The combination of a printing device having a cooperating pair of keepers thereon, one of said keepers having an embossage therein providing a projection, a tab including a stem portion adapted to be neatly fitted between said keepers, said tab having an embossage therein providing a pocket adapted to cooperate with the projection on said keeper when said stem is disposed between said keepers, said tab having another embossage therein transversely aligned with the first embossage and providing a projection adapted to cooperate with the adjacent part of the printing device to position said tab in said keepers with the pocket on the tab in engagement with the projection on the keeper.

11. A printing device tab having a stem, said stem having an embossage therein at a side edge thereof.

12. A printing device tab having a stem, said stem having embossages therein, the relief faces of said embossages projecting in opposite directions from said stem.

13. A printing device tab having a stem, said stem having embossages therein in transverse alignment thereon, the relief faces of said embossages projecting in opposite directions from said stem.

14. A printing device tab having a stem, said stem having embossages therein in transverse alignment thereon and at the side edges thereof, the relief faces of said embossages projecting in opposite directions from said stem.

JAMES P. JACKSON.
